UNITED STATES PATENT OFFICE.

THOMAS J. STEARNS, OF BOSTON, MASSACHUSETTS, ASSIGNOR TO ROXBURY CARPET COMPANY, OF SAME PLACE.

DESIGN FOR CARPETS.

SPECIFICATION forming part of Design No. 11,802, dated June 1, 1880.

Application filed April 7, 1880. Term of patent 3½ years.

To all whom it may concern:

Be it known that I, THOMAS J. STEARNS, of Boston, in the county of Suffolk and State of Massachusetts, have invented a new and original Design for Carpets, of which the following is a specification.

The nature of my design is fully shown in the accompanying photographic illustration, forming a part of this specification.

10 The design is composed of rectangular figures C, ornamented by herring-bone lines, the figures C', ornamented by circular spots, the figures D, ornamented by diagonal zigzag lines, the curved figures or borders F, the larger diagonal figures C'', ornamented by floral designs, 15 the light figures B, partially covered by foliage, and the intermediate spaces, ornamented by the large roses A and other floral designs.

My Patent No. 10,606, March 26, 1878, shows a large variety of ornamented figures, differing, however, in arrangement and ornamentation from the present design. I therefore disclaim the form and arrangement of figures shown in said patent. 20

I claim—

The design for a carpet substantially as herein shown and described.

In testimony whereof I have signed my name to this specification in the presence of two subscribing witnesses this 1st day of April, 30 A. D. 1880.

THOMAS J. STEARNS.
